UNITED STATES PATENT OFFICE.

GEORGE DAVIDSON, OF PARIS, ONTARIO, CANADA.

STOP-MOTION MECHANISM FOR CIRCULAR-KNITTING MACHINES.

SPECIFICATION forming part of Letters Patent No. 355,596, dated January 4, 1887.

Application filed July 29, 1884. Serial No. 139,061. (No model.)

To all whom it may concern:

Be it known that I, GEORGE DAVIDSON, of Paris, Province of Ontario, Dominion of Canada, have invented a new and useful Improvement in Stop-Motion Mechanism for Circular-Knitting Machines, of which the following is a specification.

My invention relates to apparatus for operating the usual and ordinary stop-motion mechanism of circular-knitting machines. This apparatus, to which my invention as an improvement relates, consists of a pivoted lever that is drawn out by its handle against the force of a spring to put on the driving-belt of the machine from which power is derived, and which lever engages with a pivoted latch that is held down to its engagement by a latch-pin on a tripping-rod to keep the driving-belt on and the lever drawn out, the said tripping-rod being arranged between the vertical sides 15 of an inverted-U-shaped standard, with bearings in the top of the latter, and at the bottom of said standard, so that the said tripping-rod can be turned therein to release the latch-pin 20 and lever, and thus trip the lever and throw off the driving-belt of the machine, to stop the rotation of the latter.

To provide improved means for automatically operating the hereinbefore-described shifting mechanism when a yarn is broken or the 30 bobbin has been run off is the object of my invention.

My invention, therefore, consists in the novel construction of the parts and their combination, as will be hereinafter fully disclosed, and 35 specifically, as is pointed out in the claims made hereto.

Accompanying this specification, to form a part of it, there are three plates of drawings 40 containing six figures, illustrating my invention, with the same designation of its parts by letter-reference used in all of them. Of these illustrations, Figure 1 shows a side elevation of a part of a rotary knitting-machine with 45 the ordinary stop-motion connected therewith, and showing also my invention applied thereto to operate said stop-motion. Fig. 2 illustrates a plan view of a part of the machine-table and the bed of the machine partly in 50 section, and showing also the pivoted belt shifting or shipping lever with the adjustable

bracket affixed thereto, the latch-pin, the latch, the tripping-rod, and the spring connected to the lever. Fig. 3 shows, as detached from the machine, a view of a pivoted lever that is operated to trip the belt by turning the tripping-rod. Fig. 4 shows, as detached from the machine, a view of a pivoted drop-catch, a series of which are arranged on the side of the knitting-machine cylinder, that shown in this representation being illustrated in larger proportion than those upon the cylinder, to better show its details. Fig. 5 is a perspective of a pivoted yarn-holder constructed with an angular end and an offset-arm. This figure illustrates also the plate by which the said yarn-holder is connected to a supporting standard and made adjustable thereon. Fig. 6 is an enlarged detail view in perspective, showing the yarn-guides, the bracket carrying the yarn-holder, and a part of a cylinder with a pivoted catch thereon.

The several parts of the knitting-machine, its stop-motion mechanism, and the apparatus containing my invention for operating the 75 same are designated by letter-reference, and their function is described as follows:

The letter C designates the machine-cylinder, N the needles, W the web, and T the machine-table.

The stop-motion is designated as follows, the letter U indicating an inverted-U-shaped standard attached to the table, R the tripping-rod adapted to turn in the top and bottom of said standard, and P a horizontally-projected latch-pin on said tripping-rod.

The letter L designates the latch of the stop-motion mechanism, said latch being pivoted at o in the brackets b b, attached to the standard U.

The letter I indicates a belt shifting lever, which is pivoted at M, and S indicates a spring, which at its inner end is connected to a ring through which the machine-shaft passes, and at the other end to the said lever I, so that said lever is drawn out by its handle H to put on the belt against the force of said spring.

The letter O designates an adjustable bracket on the said lever, the inner end of which presses against the latch L when the inner end of the latter is beneath and held down by the latch-pin P. Thus when the lever is drawn out to

put on the belt it is held so as to keep the belt on and the machine running by the engagement of the bracket O on the said lever with the latch L, and the engagement of the latter 5 with the latch-pin P on the tripping-rod R. Now, when the rod R is turned by any means, its latch-pin P runs from off the end of the pivoted latch L, the latter turning upwardly 10 on its outer end by the pressure of the spring lever, and the latter slips from off the latch, the lever being drawn inwardly by the spring to unship the belt.

To automatically operate the tripping-rod to throw off the belt and stop the machine 15 when a thread of yarn is broken or fails in continuity to feed the machine, I employ the following mechanism.

The letter J designates a series of catches that are arranged on the exterior of the knitting-machine cylinder, each of which is pivoted at t, so that they can be turned down on 20 their pivotal connection, and the letter i' indicates an incline projected upwardly from the machine-table, which engages with the under 25 side of said catches to turn them up, so as to bring their lower surface parallel with the bottom edge of the knitting-machine cylinder after having been turned down.

The letter d designates a lateral projection 30 made on the outer face of each of the catches.

The letter A indicates a standard, upon which, by means of a bracket, B, there is attached an upright plate, m, having adjustably pivoted thereto a yarn-holder, h. This yarn-holder is provided with a projecting arm, a², 35 and is pivoted at its upper end in the holder-plate m at r, and at its lower end is formed with an angular termination, p², the purpose of the termination being to keep the holder 40 resting on the yarn as the same is passing into the machine between the yarn-guides n n. When the angular termination p² is on the yarn, the holder is held up, and when the yarn breaks or fails to hold up the yarn-holder the 45 yarn-holder falls to a vertical position, the upper part resting in the recess l of the projection p³ on the holder-plate m, the projecting arm a² pointing inward toward the cylinder C. When the yarn-holder h is thus down, 50 its arm a², as the machine revolves, comes in contact with the next one of the catches J, to engage with its top rounded surface, k, so as to force downwardly the catch, as shown at J' of Fig. 1.

The letter E designates a curved lever formed 55 with the turned-up ends e' and e², and pivoted to the standard G at g, so as to be horizontally moved outwardly and inwardly at its ends.

The letter K designates a projecting arm on 60 the tripping-rod R of the belt-shipping mechanism.

The operation of the mechanism thus constructed to operate the tripping-rod is as follows: When the yarn Y is regularly passing 65 into the machine, the angular end of the holder h rests on the yarn at a point between the two yarn-guides n n, and when the yarn breaks or

ceases to sustain the holder h the latter falls on its pivoted connection, and in its descent its arm a² is carried into position to engage 70 with and turn down on its pivoted connection the adjacent one of the series of catches J, brought in contact with said arm a² by the revolution of the machine-cylinder. When this dropping catch falls, a projection, d, on its 75 side engages with the upturned end, e', of the curved lever E, forcing this engaging end outwardly, and the opposite upturned end, e², to engage with the arm K of the tripping-rod R, so as to force the latter around on its pivotal 80 connection, releasing the latch-pin, latch, and belt-shipping mechanism to stop the machine.

Where yarn breaks or fails to be supplied to the machine in continuity, blemishes and irregularities occur in the web, and to avoid 85 these contingencies by the automatic operation of the machine is what my invention is designed to effect.

I am aware that a mechanism has been used which consists of yarn-holders hinged to a 90 frame, and which holders, when released by a break in the yarn, fall down upon one side of a pivoted balance, to raise the other side of the latter and engage with one of the nuts on the machine-cylinder, so as to turn said frame 95 and balance horizontally, which, being connected with an arm on the tripping-rod, are thus caused to trip the belt-shipping mechanism and stop the machine.

Having thus described my invention, what 100 I claim, and desire to secure by Letters Patent, is—

1. The combination, with the belt-shipping mechanism and the cylinder of a rotary knitting-machine, of a yarn-holder pivotally supported and formed with an angular termination at its free end and an intermediate laterally-projecting arm, catches pivoted to the outer face of the cylinder, and a trip-lever having upturned ends to engage with the said 105 catches, substantially as described.

2. The combination, with the belt-shipping mechanism and the cylinder of a rotary knitting-machine, of a yarn-holder pivotally supported and formed with an angular termination at its free end and an intermediate laterally-projected arm, catches pivoted to the outer face of the cylinder and having cam-surfaces k and projecting pieces d, and the lever E, substantially as described. 115

3. The combination, with the cylinder of the machine and the table thereof, of the catches J, pivotally attached to the cylinder, and the incline i', fixed on the table, substantially as described, and for the purpose stated. 120

Signed at Paris, Province of Ontario, Dominion of Canada, this 27th day of May, 1884, and in the presence of the two witnesses whose names are hereto written. 125

GEORGE DAVIDSON.
